UNITED STATES PATENT OFFICE.

JAMES R. HINKSON, OF BROOKLYN, NEW YORK, ASSIGNOR TO LOUISE MARIE STRUNCK, OF KINGS COUNTY, NEW YORK.

MOISTENER.

Application filed April 11, 1925. Serial No. 22,462.

To all whom it may concern:

Be it known that I, JAMES R. HINKSON, a citizen of the United States, and a resident of the city of New York, borough of Brooklyn, in the county of Kings and State of New York, have invented new and useful Improvements in Moisteners, of which the following is a full, clear, and exact description.

10 This invention relates to moisteners, and has particular reference to moisteners of the character used for moistening tobacco products and for flavoring the tobacco products.

15 One object of the present invention is to produce an article of the character mentioned which will obviate the use of absorbent material.

Another object of the invention is to 20 produce an article of the character mentioned which is freely movable and in which the moistening or flavoring liquid is free, which embodies means by virtue of which the moisture resulting from the evaporation 25 of the liquid will be liberated, while the liquid is prevented from escaping irrespective of the position of the article.

Another object of the invention is the use 30 of a hollow body of transparent material so that the moistening fluid used may be observed, to the end that the supply may be replenished at the proper time.

With the foregoing, other objects of the 35 invention will appear from the embodiment of the invention which, by way of example, is described in the following specification and illustrated in the accompanying drawing, in which:

Figure 1 is a side elevation of the moistener of the present invention;

40 Fig. 2 is an end elevation;

Fig. 3 is a central longitudinal sectional view through the moistener;

45 Fig. 4 is a collective view of the several parts of the moistener detached from each other.

Referring now more particularly to the several views of the drawing for all of the details of the article of the present invention, it will be apparent that the same comprises an open-ended hollow body or barrel 10 and a plurality of traps 11, which combine with the hollow body or barrel 10 to confine a quantity of liquid, such as water 50 or brandy, and to liberate moisture result-

ing from the evaporation of the liquid. In the present instance, the hollow body or barrel 10 is preferably round in cross section, and each end is provided with screw threads 12. The hollow body or barrel 10 60 is made preferably of some suitable transparent material, such as glass. Each of the traps 11 comprises a cap or closure member 13 and a tube or hollow extension 14. The cap or closure 13 is provided with screw 65 threads 15 and is knurled as at 16. The tube 14 is carried by the wall 17 of the cap and the same may be attached thereto in any suitable manner, or may be formed integral therewith, as shown, so as to be disposed axially and to extend from one side of the wall 17 at the side which carries the portion having the screw threads 15. The tube 14 in the present instance is tapered 70 with the smallest end, cross-sectionally considered, away from the wall 17. As stated, the traps 11 are identical in construction and one is arranged at each end of the hollow body or barrel 10. Each trap is employed by simply screwing the cap 13 on to the end of the barrel 10 by virtue of the screw threads 12 and 15, respectively, on the barrel end and cap. A suitable resilient gasket 75 18 is arranged in each cap 13, and is disposed between the wall 17 and the end of the barrel 10 when the cap is screwed home. When the traps 11 are applied to the hollow body or barrel 10, the tubes 14 will be in axial alignment and will be disposed interiorly of the hollow body or barrel 10, as most clearly 80 shown in Fig. 3. The caps not only serve to support the tubes 14, but also serve as closures for the opposite ends of the hollow body or barrel 10. It is also to be noted that the opposed extremities of the tubes 14 are 85 in spaced relationship.

By removing one of the traps 11, a quantity of liquid, such as water or brandy, may be introduced into the barrel 10, after which the trap may be applied. The barrel 10 is only partly filled with the liquid, as shown in Fig. 3. By virtue of the use of the traps 11, the liquid is held against egress yet the moisture resulting from the evaporation of the liquid will be readily liberated through the tubes 14. By having the tubes 14 tapered, it is possible to put more liquid into the barrel 10 than would be possible were the tubes 14 of uniform diameter equal to that 90 at the large end. Egress of the liquid is 95 100 105 110

prevented irrespective of the position in which the article is held, thus making it easy to place the moistener in different containers of tobacco products for the moistening thereof. By having the barrel 10 of transparent material, the condition of the moistener may be observed at all times and the proper amount of liquid may be kept therein. Different kinds of liquid, such as brandy, may be used for flavoring the tobacco, and the use of absorbent material is obviated.

What is claimed is:

A moistener comprising a hollow body open at each end, and traps which combine respectively with the opposite ends of the

body, each trap comprising a cap removably attached to its related end of the body, a tubular member extending laterally from one side of the end portion of the cap so as to be disposed internally of the hollow body when the cap is attached, said tubular member being of smaller diameter than the internal diameter of the hollow body, said tubular member being opened through the end portion of the cap, the caps and tubular members as attached combining with the hollow body to confine a quantity of liquid and to liberate moisture resulting from the evaporation of the liquid and to prevent the egress of the liquid.

JAMES R. HINKSON.
